UNITED STATES PATENT OFFICE.

WILLIAM HEUERMANN, OF SEDALIA, MISSOURI.

STOVE.

SPECIFICATION forming part of Letters Patent No. 739,177, dated September 15, 1903.

Application filed May 2, 1903. Serial No. 155,304. (No model.)

To all whom it may concern:

Be it known that I, WILLIAM HEUERMANN, a citizen of the United States, residing at Sedalia, in the county of Pettis and State of Missouri, have made certain new and useful Improvements in Stoves, of which the following is a specification.

My invention is an improvement in stoves, having for an object, among others, to provide a novel construction whereby to secure the maximum heating results by means of a circulation of air and by the introduction of drum sections and tubes, as will be described; and the invention consists in certain novel constructions and combinations of parts, as will be hereinafter described and claimed.

In the drawings, Figure 1 is a perspective view of a stove embodying my invention. Fig. 2 is a cross-section thereof on about line 2 2 of Fig. 1. Fig. 3 is a vertical cross-section on about line 3 3 of Fig. 2, and Fig. 4 is a detail perspective view of the inner side of one of the hinged drum-sections.

In carrying out my invention I make the stove in two sections, an upper section A and the lower section B, the latter including the fire-box B', with its grate B'', and the fire-door B''' and the damper devices B⁴ opening below the grate B'', as will be understood from Figs. 1 and 2. The upper section A is preferably hinged at its rear edge at A' to the upper edge of the section B, so the section A may be turned back on its hinge A' to expose the entire interior of the section B and of the section A whenever desired. The section A immediately above the fire-box is provided with a tube D, extending from front to rear of the section A and opening at its ends to the atmosphere. This tube D may be made of any suitable cross-sectional shape, although for convenience in manufacture it may be preferred to make it round, as shown in Figs. 1, 2, and 3. This tube operates to secure good heating results by the circulation of the air from end to end and through the stove, and it also operates to throw the heat out next to the walls of the stove and adjacent to the inner faces of the opposite side flue-sections, presently described. At its upper end the stove is shown as rounded from front to rear and provided at its rear side with the offtake E, which may be in the form of a

nipple for the connection of a stovepipe, as shown. A cross-flue F extends from side to side of the stove, is open at its ends where it abuts the drum-sections, presently described, and is provided in its lower side, practically in register with the offtake E, with an opening F', controlled by a damper or valve G, having a rod G' extending outside the stove, so the damper G may be opened whenever it is desired to establish direct communication between the interior of the stove and the offtake E in the use of the invention.

The drum-sections H and I are arranged at the opposite sides of the stove and may, if desired, be hinged at one edge at H' to the body of the stove and provided at the other edge with a latch H'', so the drum-sections can be opened to permit access to the interior of the top section of the stove whenever desired. These drums have a generally circular form and round outwardly from their outer edges toward the center and are provided at their centers with the conical inwardly-flared radiating-surfaces h and i, which are in alinement and may be connected at their inner ends by means of a bolt J, as shown. The drum-sections H and I are substantially alike, being formed to provide a curved flue having the inlet-opening h' or i', the discharge-opening h² or i² registering with the ends of the cross-flue F, said inlet and outlet opening being separated by partitions h³ or i³, so that the hot air, smoke, &c., entering the openings h' and i' will be forced to travel around the drum-sections and discharge at h² or i² to the ends of the cross-flues F, as will be understood from Figs. 2, 3, and 4 of the drawings. Openings h⁴ and i⁴ may be provided between the inlet and discharge openings and controlled by valves h⁵ and i⁵ to secure a quicker draft whenever desired, also for cleaning.

In the operation of my invention it will be noticed the drum-tube D in addition to heating the air which passes through it will force the heat out toward the inner sides of the drum-sections H and I, so the heat will be caused to pass to the inlet-openings of said sections and then around the drums and from the discharge-openings thereof to the ends of the cross-flue and thence out the offtake, provided the dampers G, h⁵, and i⁵ are closed.

If the dampers h^5 and i^5 are open, the heat will be caused to pass more directly to the discharge-openings h' and i' , while if the damper G be open the heat will pass directly from the offtake. The conical or funnel-shaped centers of the drum-sections operate in a measure as reflectors for the purpose of throwing out the heat and improving the results secured in the use of the invention.

10. Having thus described my invention, what I claim as new, and desire to secure by Letters Patent, is—

15. 1. The improvement in stoves herein described, comprising the lower section having the fire-box, the upper section hinged to the lower section, and provided with the drum-tube extending from end to end and opening at its ends to the atmosphere, the offtake at the top of the upper section, the cross-flue below the offtake and extending from side to side of the stove, and provided with a damper in line with the offtake, the circular side or drum sections having the central conical or funnel-shaped reflectors, and provided with the flues encircling the reflectors and having the discharge-openings in register with the ends of the cross-flue, and the inlet-openings adjacent to the discharge-openings and the partition crossing the flue between the said 30 openings, and the rod connecting the said flue-sections at the centers thereof, substantially as set forth.

20. 2. A stove having a flue-tube extending from front to rear and open at its end and arranged to deflect the heat toward the sides of the stove, the drum-sections at the opposite sides of the stove and alongside the drum-tube, and arranged to receive the heat de-

flected thereby, and provided with inlet and discharge openings, the cross-flue registering with the discharge-openings of the drum-sections, and the offtake, substantially as described.

25. 3. A stove having a flue-tube extending through it and a drum section or sections to which the heat is deflected by the sides of said drum-tube, substantially as described.

40. 4. A stove having the opposite drum-sections, provided with the central conical or funnel-shaped reflectors and with the flues surrounding the same, and having inlet and discharge openings leading to said flue, substantially as described.

45. 5. The combination in a stove, of the stove-body having the cross-flue, and the offtake communicating therewith, and the opposite drum-sections having the funnel-shaped reflectors, and the flues surrounding the same, and the rod connecting the inner ends of the funnel-shaped reflectors, substantially as set forth.

50. 6. The combination of the stove-body, the flue-tube extending from front to rear thereof and open at its ends, and the drum-sections at the opposite sides of the stove and on opposite sides of the flue-tube, and having the funnel-shaped reflectors extending at their inner ends above the flue-tube, and connections between the inner ends of the funnel-shaped reflectors, substantially as set forth. 70
